(57) **CLAIM**

The ornamental design for an surface ornamentation for an automobile and/or toy replica thereof, as shown and described.

DESCRIPTION

FIG. 1 is a left side view of an surface ornamentation for an automobile and/or toy replica thereof showing our new design;

FIG. 2 is a right side view thereof;

FIG. 3 is a top plan view thereof;

FIG. 4 is a front view thereof; and,

FIG. 5 is a rear view thereof.

The broken lines are shown for illustrative purposes only and form no part of the claimed invention. The dash-dotted lines define the boundary of the claimed design.
